UNITED STATES PATENT OFFICE.

EDMUND R. BARANY, OF BROOKLYN, NEW YORK, ASSIGNOR TO FRANCO ELECTRIC CORPORATION, A CORPORATION OF NEW YORK.

FLASH LIGHT.

Application filed December 21, 1921. Serial No. 523,841.

To all whom it may concern:

Be it known that I, EDMUND R. BARANY, a citizen of the United States, and resident of the borough of Brooklyn, county of Kings, 5 city and State of New York, have invented certain new and useful Improvements in Flash Lights, of which the following is a specification.

This invention relates to flashlights and 10 has for an important object the provision of a means by which the rays of light emitted by the several lamps are focused upon or converged at some distant point beyond the center of curvature of the several reflectors 15 which are employed.

A further object of the invention is to provide a novel means of supporting a plurality or group of reflectors in such a way that the beams of light reflected thereby are 20 concentrated upon a relatively small area.

Other objects of the invention will become apparent from the following description taken in connection with the drawings in which;

25 Figure 1 is a plan view of a flashlight embodying my invention.

Figure 2 is a fragmentary longitudinal sectional view taken on line 2—2 of Figure 1.

30 Figure 3 is a diagrammatic view illustrating the circuits for the various lamps and the manner in which the light rays are focused upon a given point or area.

Figure 4 is a sectional view taken on line 35 4—4 of Figure 2.

In the drawing the numeral 10 indicates a casing in the form of an elongated cylindrical tube, preferably constructed of fibre or other suitable insulating material within 40 which is arranged a battery 11 comprising a plurality of cells 12, each of which employs the usual form of zinc container 13 and carbon electrode 14.

Upon one end of the casing 10 there is 45 mounted a reflector head 15 which at its outer end is screw threaded as shown at 16 and adapted to receive thereupon the usual form of lens ring 17, which is provided with

an inwardly projecting flange 18 adapted to engage a lens hereinafter more particularly 50 described.

To the inner surface of the casing 10 at one end thereof there are secured a plurality of conductor strips 19 corresponding in number to the number of lamps employed. 55

These conductor strips are bent outwardly at their outer ends through openings 20 formed in the casing 10 and engage the usual central contact of the lamps 21. The lamps 21 as shown are supported by the reflectors 22, and are maintained in screw threaded engagement with the reduced or screw threaded portions of the reflectors as shown at 23. The reflectors 22 which are so disposed that their axes converge toward 60 a common point as illustrated in Figure 3, are carried by a reflector plate 24 from which they may be stamped or to which they may be independently secured as by soldering or the like. The reflector plate 24 as shown 65 in Figure 2 is slightly concaved and is adapted to receive thereupon a lens 25 which engages the reflector plate 24 at the periphery thereof and is maintained in firm engagement therewith by means of the lens ring 70 17. It will be noted that the reflector plate 24 is spaced an appreciable distance from the lens ring 17 at its periphery to prevent short circuiting of the current as will be more fully appreciated when considering the 75 wiring diagrams shown in Figure 3. By reason of the fact that the reduced portions 23 of the reflectors 22 extend only a slight distance into the openings 20 within which they snugly fit, it is apparent that the reflector plate 24 will assume a central position with respect to the outer end of the reflector head 15 when the central contacts of the lamps 21 engage the outer ends of the conductor strips 19. In assembling the device 80 the reflector plate 24 and reflectors 22 are forced to assume given positions, these positions being maintained by reason of the peripheral engagement of the reflector plate 24 with the lens 25 which is retained firmly 85 seated with the lens ring 17.

The several cells 12 comprising the battery 11 are inserted in the casing 10 by removing the usual screw threaded cap 26 diagrammatically illustrated in Figure 3 which is 5 provided with the conventional thrust spring 27 and when so inserted the carbon electrode 14 of the uppermost cell shown in Figure 3 electrically engages a more or less resilient contact strip 28 which is bent substantially 10 at a right angle and secured to the casing 10, the conductor strip being again bent and passed through an opening 29 formed in the casing in order that the same may electrically engage one of the reflectors 22 as 15 clearly shown in Figure 2.

I have illustrated only diagrammatically the switch 30 for controlling the circuits through the several conductors 31 leading to the conductor strips 19 which are electrically connected with the lamps 21, inasmuch as the device embodying my invention is not restricted to any specific design in this connection. It may be well to mention however, that the switch 30, having a plurality of 20 circuit closer arms 32 which correspond in number to the number of conductors 31, may be actuated to place either one or more of the lamps 21 in circuit with the battery 11 through the reflectors 22, reflector plate 24, 25 conductor 28, one or all of the conductors 31 and the conductor 33 which is connected at one end to the switch 30 and at its opposite end to the zinc electrode of the lowermost cell 12 in the usual manner. It will 30 be readily appreciated that, by reason of the angular disposition of the reflectors 22 and the provision which is made for maintaining a plurality of lamps in circuit at the same time, I am enabled to concentrate the light 35 rays from the plurality of lamps upon a given area and thus intensify the illumination at the point of concentration. But on the other hand, should it be desired to direct the light upon a point other than that 40 at which the axes of the various reflectors converge, the flashlight as a whole may be so handled as to project the light rays from a single lamp upon the desired point or area.

A device embodying my invention above 45 described may employ a plurality of reflectors arranged to concentrate the light rays emitted by their respective lamps at any desired point remote thereto, the point of concentration being dependent of course, upon 50 the angular relation of the reflector axes with respect to the longitudinal axis of the casing 10. For example, should it be desired to concentrate the light upon a given point relatively close to the lamps the reflectors may be set at a greater angle with 55 respect to the axis of the casing than is required if the point of concentration is to be located at a point more remote to the lamps. 60 Inasmuch as certain requirements will determine the location at which the light rays

are to be concentrated, I do not wish to limit myself to any particular angular disposition of the reflectors 22 and in this connection it may be pointed out that the point of light concentration illustrated in Figure 3 is represented primarily to illustrate somewhat exaggeratedly the fact that the light rays converge forwardly upon an area remote to the lamps. 70

Having thus described my invention, I 75 claim:

1. A flashlight comprising a casing adapted to receive therein a battery, a plurality of lamps grouped about the axis of said casing, reflectors associated with said lamps 80 for reflecting the light rays thereof, and a reflector rigidly connected plate supporting said reflectors for supporting and retaining them in such positions that their axes intersect at a point on the axis of said casing an 85 appreciable distance beyond the end thereof.

2. A flashlight comprising a casing, a reflector head, a reflector plate associated with said head, means for retaining said plate centrally disposed with respect to the axis 90 of said casing and head, a group of independent reflectors rigidly attached to said plate, the axes of said reflectors being disposed at a relatively small angle with respect to the axis of said casing, and a plurality 95 of lamps so associated with said reflectors that the light rays emitted thereby are concentrated upon a given area relatively remote to said head.

3. A flashlight comprising a casing, a reflector head, a slightly concaved reflector plate associated with said head, means for retaining said plate centrally disposed with respect to said casing and head, a group of independent divergently disposed reflectors 105 rigidly attached to said plate, the axes of said reflectors being disposed at a relatively small angle with respect to the axis of said casing and plate, and a plurality of lamps so associated with said reflectors that the light rays emitted thereby are convergently directed to and concentrated upon a 110 given area relatively remote to said head.

4. A flashlight comprising a casing, a reflector head, a removable reflector plate associated with said head, means for supporting said plate in a centrally disposed relation to the axis of said casing and head, means for retaining said plate centrally disposed with respect to the axes of said casing and head, a group of divergently disposed reflectors rigidly attached to the said plate, the axes of said reflectors being disposed at a relatively small angle with respect to the axis of said casing, and a plurality of lamps 120 so associated with said reflectors that the light rays emitted thereby are centered upon a given area relatively remote to said head. 125

5. A flashlight comprising a casing, a reflector head, a slightly concaved reflector 130

plate associated with said head but insulated therefrom, a group of divergingly disposed reflectors carried by said plate, said reflectors being formed integral with said plate and having their axes disposed at a relatively small angle with respect to the axis of said casing, head and plate, and a plurality of lamps so associated with said reflectors that the light rays emitted thereby are centered upon a given area relatively remote to said head.

In testimony whereof, I have affixed my signature to this specification.

EDMUND R. BARANY.
